UNITED STATES PATENT OFFICE.

CHARLES W. ANDREWS, OF DULUTH, MINNESOTA, AND WILLIAM B. CHAPMAN, OF JACKSON HEIGHTS, NEW YORK, ASSIGNEES OF ONE-HALF TO H. A. BRASSERT & COMPANY, A CORPORATION OF ILLINOIS, AND ONE-HALF TO THE WESTERN GAS CONSTRUCTION COMPANY, A CORPORATION OF INDIANA.

METHOD OF GENERATING GAS.

Application filed July 3, 1926. Serial No. 120,291.

The primary object of the invention is to provide a method whereby a gas generator may be operated under such conditions as to so control the formation of clinkers as to prevent the formation of the large clinkers which tend to form in the ash bed, and lower portion of the fire bed in usual methods of operation. Particularly in the production of water gas, clinkers of such large size have been formed that it has been necessary to shut down the generator periodically and take out the clinkers manually with bars and sledge hammers.

We have illustrated in the accompanying drawings a gas generator adapted to be operated in accordance with the invention, but it should be understood that this particular gas generator is merely typical of an apparatus suitable for carrying out the invention, and that the principles of the invention are not confined thereto. In the drawings—

Fig. 1 is a central vertical sectional view showing the general construction of a gas generator adapted to be operated in accordance with the invention.

Figs. 2 and 3 are vertical sectional views, partly diagrammatic, respectively showing the full height of a water gas generator and gas producer adapted to carry out the process of the present invention.

Gas generators have been operated with relatively thick ash beds, with the result that the ash in the lower parts of the ash bed has been relatively cold, and although such ash beds have been agitated to some extent from underneath, this agitation has not proved effective in breaking up very large clinkers particularly in water gas generation when once they have been formed, and the effort has generally been made to minimize the formation of large clinkers by keeping the temperatures within the generator as low as possible while still within the limits necessary for producing a commercial grade of gas, the idea being that if the ash content of the fuel bed was kept below its liquefying temperature, there would not be so many large clinker masses formed. Moreover it has been customary to operate water gas generators, so as to maintain under the fire bed a bed of thoroughly burned fuel deep enough to submerge the ash agitator

member, thereby rendering it unnecessary to water cool said member.

According to the present invention the gas generator is operated under such conditions that the temperature of the hottest zone of the fuel bed for the most part is well above the liquefying point of its ash content, whereby liquid ash tends to run down in little rivulets from the hottest zone of the fuel bed, to a slightly cooler zone directly beneath the same which latter zone, although somewhat below the liquefying point of the ash, nevertheless is sufficiently hot to permit the liquid ash, trickling into said zone, to continue its downward flow without losing its mobility until it reaches the small clinkers and partially burned fuel in the neighborhood of the agitating member, and agitated by it. The melting point of ash in different grades of coal and coke as usually employed, runs between about 1900-2700° F. This zone of the ash bed is then subjected to the direct action of an agitating member which sweeps through the slowly solidifying ash, before it can run together and solidify into large masses that cannot be readily broken up.

We prefer to operate the gas generator in such manner that a very thin ash and clinker bed is maintained. It is not allowed to become thick as is customary in prior practice. The solidifying zone above mentioned will then be located almost upon the grate of the generator, such zone being made up of partially consumed fuel, small clinkers and ash at red heat, with the result that the generator has no thick cold ash bed as heretofore. The agitating member, located directly over the generator grate, is where it will continually break up clinkers as aforesaid, and also thoroughly agitate the lower portion of the fire bed and assist in the uniform removal of the clinker and ash due to its up-and-out-stroking action, thereby maintaining good gas making conditions in the fire bed. The thin ash bed and the continuous agitation of the fire bed make it possible to carry a greatly reduced depth of fire.

By supplying air in sufficient quantity to maintain an ash liquefying zone in the fuel bed, and ejecting clinker and ash at such rate that the solidifying zone will be shallow and

kept at a proper heat, the same agitating member may serve to perform continuously all of the above mentioned functions of preventing the formation of large clinkers by 5 breaking up the clinkers as they form, agitating the fuel bed and assisting in the removal of the clinker and ash. For example, from 10 30 to 50 cubic feet of air (at atmospheric pressure and room temperature) may be used per pound of total steam, the smaller amount 15 of air being used for fuel of low ash melting point and the larger amounts for fuels of higher ash melting point. Agitation in this invention is not "through the medium of the ash" as heretofore, but mostly through the medium of the partially consumed, but still 20 burning, fuel.

The amount of steam fed into the bottom 25 of the generator may also be regulated to 20 control temperature conditions within the generator, the steam acting as a cooling medium, whereas the air fed in acts as a heating medium.

In the production of water gas, furthermore, the up and down runs may be proportioned to maintain ash liquefying and solidifying temperature conditions as above described, so that the clinkers will be properly broken up by the agitating member. The 30 production of water gas usually involves a cycle of operations over a period of three to eight minutes, the first operation being the passing of a blast of air upwardly through the ash and fuel beds, another operation being 35 an upward run of steam, and a third operation being a downward run of steam, the above operations usually taking up about the same amount of time, the up and down steam being about the same in quantity, according 40 to prior practice.

In accordance with the present invention the upward blast of air will be sufficient in quantity to raise the hottest zone in the fuel bed to such a temperature as may be required 45 to liquefy the major portion of the ash content of the fuel bed. This temperature, with some grades of coke, may be for example, from about 2700° to 3000° F. The quantity of the up-run-steam may be (but is not necessarily) substantially lessened to assist in preventing the lower zone in the fire bed from cooling off sufficiently to unduly check the flow of the molten clinker streams before coming within the radius of action of the 50 agitating member. Good results have been obtained with but twenty (20) per cent of up-steam. This makes a sufficiently increased proportion of down-steam, so that it will carry down from the upper zones sufficient sensible heat to assist materially in maintaining at a red heat the major portion of the clinker and ash upon the grate. Because of the high temperature maintained in the bottom of the fire, the steam up-runs may 55 be entirely omitted if blue water gas is de-

sired, or if the gas connections are arranged to pass part or all of the down-run water gas through the carburetor. This does not preclude removing gas from the ash pit by up-purges. This unusually large percentage of 70 down run steam greatly increases the efficiency of water gas generation. The usual practice in the operation of present day water gas generators involves not more than a 60% ratio of down-run steam to total steam supplied. 75

It has been found with certain fuels that gases made in a deep fire bed of the above description, are exceptionally rich in quality, the air blast gases being too high in 80 carbon monoxide for most efficient operation.

A substantially thinner fire bed has resulted in substantially reducing the richness of the blast gases, which pass through the fire bed at high velocity, without materially reducing 85 the richness of the up and down-run water gases, which pass through the fire bed comparatively slowly. The exceedingly high temperature described above and the uniform condition of the fire bed, due to continuous agitation, render it unnecessary with some fuels to carry the usual depth of fire bed, which is eight (8) to ten (10) feet, in order to obtain a satisfactory quality of 90 gas; a satisfactory quality of gas has been 95 obtained with one half the usual depth of fire bed. This reduces the pressure drop through the fire bed and also reduces the combustible content of the blast gases leaving the fuel bed, thus increasing the efficiency 100 of the operation by developing more heat in the fire bed, and carrying away less energy in the blast gases. For example, the blast gases may contain about 14% CO and 14% 105 CO₂.

The invention as illustrated may be carried out in a gas generator similar to the one more fully described in our copending application, Serial Number 737,238, filed September 12, 1924, entitled "Gas generator" 110 and accordingly the structural features of the generator will be described only in a general way herein. The gas generator is shown as provided with side walls 1 enclosing the fuel and ash beds and a stationary 115 grate 2 through which air and steam will be passed as previously described in connection with the production of water gas. As shown a distributing chamber 3 underlies the grate 2 and is surrounded by an annular ash chamber 4 into which a portion of the ash will be deposited as hereinafter described. A certain amount of ash will also pass down through the grate 2 into the chamber 3. 120

The agitating member 5 is shown in the 125 form of a water cooled beam extending substantially diametrically over the grate and secured to a drive ring 6 which surrounds the grate and is rotatably mounted upon the bearing ring 7. Suitable water cooling con- 130

nections 8 may be led through chamber 3 to the agitating member.

In the operation of the generator a zone 9 of the fuel bed which extends down approximately to the line 10 indicated on the drawings, will be maintained at a heat sufficient to liquefy at least most of its ash content, with the result that small streams of the liquid ash run down into the bed or zone 11 beneath the line 10 indicated upon the drawings, which is maintained at a temperature somewhat below the liquefying temperature of the ash (2000° F. more or less, depending upon the melting point of the ash), but yet at a red heat sufficient to prevent the ash from cooling and taking a set too quickly. The agitating member 5 rotates within the above mentioned zone 11 and therefore directly engages and breaks up the solidifying ash before it can form into large clinkers. The beam should be made of substantial thickness and as shown its forward surfaces preferably are inclined, whereby it exerts a substantial up-stroking effect which extends at least into the lower portion of the zone 9 and assists in maintaining good gas making conditions therein.

The beam is also outstroking in its action and tends to crowd the ash outwardly beyond the periphery of grate 2, from whence the ash may pass downwardly through an annular ash discharge opening 12 to a trough 13 provided in connection with the drive ring 5. The rate of ash removal may be controlled by removing ash in any suitable manner in measured quantities from the trough 13, thereby permitting further ash to pass out from the ash bed through the discharge opening 12.

As previously stated, the ash preferably is ejected from the generator at such rate that the zone 11, in which the agitating member operates, is maintained at a shallow depth, whereby the contents of the generator are at a red heat, substantially down to the grate 2.

As shown, the portion of the generator walls surrounding the agitating member 5, are water-cooled by means of the passages 14 in an annular wear member 15. This water-cooling tends to cool down the portion of the generator walls just above the ring 15 to such an extent that under ordinary conditions slag deposits would build up which could only be removed manually after shutting down the generator. We have found, however, that if a zone in the fuel bed be maintained well above the ash liquefying temperature, as above described, the ash will quickly flow downwardly past said cooled portion of the generator wall into the radius of action of the agitating member without forming objectionable deposits as aforesaid.

A generator, operated in the above manner,

therefore, may be run continuously, the ash being mechanically removed at the proper rate and the fuel and ash beds mechanically agitated from underneath by the beam 5, to assist in maintaining good gas making conditions.

It has long been recognized that the so-called slagging producer is the most efficient type, due to the extremely high temperatures necessary for liquefying the entire ash content of the fuel, but hitherto this type of producer has not proven commercial because of the cost and extreme difficulty of obtaining the required degree of fluidity with most fuels. A modified slagging type is now made possible by the combination of mechanical agitation and proportioning of the blast, and up and down runs above described. This improved method has all of the advantages of the slagging producer and none of its disadvantages, and therefore forms an important part of this invention.

In Fig. 2 we have shown in a general way, a water gas generator having the parts more fully described above in connection with Fig. 1, and also having in its dome at the top, a steam inlet pipe 16 and a similar steam inlet pipe 17 in chamber 3 above described. A gas and blast outlet conduit 18 is also indicated at the top, and air and gas inlet and outlet conduits 18^a at the bottom, communicating with chamber 3. Fig. 2 also shows the ash liquefying zone 9 and ash solidifying zone 10 in proper relation to the full height of the firebed, the upper zone of which firebed is illustrated at 19, and Fig. 2 also indicates diagrammatically at 20, molten ash running down from the ash liquefying zone 9 into the range of action of the agitating member 5.

Fig. 3 shows an apparatus similar to that of Fig. 2 used for making producer gas, the various numerals denoting the same parts as in Fig. 2 with the exception that the upper firebed zone 19^a of Fig. 3, will be somewhat shallower than the corresponding firebed zone 19 of Fig. 2.

While the invention has been described as carried out by means of a certain construction of gas generator, it will be obvious that many changes may be made therein without departing from its principles as set forth in the appended claims.

We claim:

1. The method of making water gas in a gas generator having a firebed containing a zone at an intermediate level extending substantially across the firebed and a zone containing ash underneath said first mentioned zone, which comprises air blasting the firebed to maintain the first mentioned zone at a temperature sufficient to liquefy a substantial portion of its ash content, passing the liquefied ash content downwardly into said second mentioned zone, maintaining the second mentioned zone at a red heat somewhat below the

ash solidifying temperature, whereby ash passing downwardly from the first mentioned zone solidifies in the second mentioned zone, and passing an agitating member through 5 said second mentioned zone to break up clinkers while hot and before large masses can form, and passing steam through the heated firebed, and thereby forming water gas.

2. The method of making water gas in a 10 gas generator having a firebed containing a zone at an intermediate level and a second cooler zone containing ash underneath said first mentioned zone, which comprises air blasting the fuel bed to maintain the first 15 mentioned zone at a temperature sufficient to liquefy a substantial portion of its ash content, passing the liquefied ash content downwardly into said second mentioned zone to solidify it, and breaking up the clinkers in 20 said second mentioned zone before large masses can form, and passing steam through the heated firebed, and thereby forming water gas.

3. The method of making water gas in a 25 generator having a firebed containing a zone at an intermediate level and a second cooler zone containing ash underneath said first mentioned zone, which comprises air-blasting the firebed, passing steam through the firebed 30 and employing more than a 60% ratio of down-run steam to total steam supplied, to maintain said first mentioned zone at a temperature sufficient to liquefy a substantial portion of the ash content of the fuel, passing 35 the liquefied ash content downwardly into said second mentioned zone, and breaking up the clinkers in said second mentioned zone before large masses can form.

4. The method of making water gas in a 40 gas generator having a firebed, which comprises removing ash from the firebed at a rate sufficient to leave only a small amount of ash at the bottom of the generator, passing air upwardly through the firebed to heat a zone 45 at an intermediate level therein to a temperature sufficient to liquefy a substantial portion of its ash content, then passing steam in upward and downward runs through the firebed, the upward run of steam being sufficiently small and the downward run sufficiently large in quantity to maintain a lower 50 zone in the firebed beneath said first mentioned zone, at a red heat somewhat under the solidifying point of the ash, passing the liquefied ash content downwardly from said first mentioned zone to said second mentioned zone, and passing an agitating member through said second mentioned zone to engage and break up the clinkers before large 55 masses can form therein.

5. The method of making water gas in a 60 gas generator having a firebed, which comprises maintaining a zone at an intermediate level in the firebed at a temperature sufficient to liquefy a substantial portion of its ash con-

tent, passing the liquefied ash content downwardly from said zone to solidify the same, removing ash from the bottom of the firebed at a rate sufficient to leave at the bottom of the generator only a small amount of ash at a 70 temperature somewhat below the ash solidifying point, passing an upstroking agitating member through the bottom of the firebed, to engage and break up the solidified clinkers which tend to form and agitate the firebed 75 from underneath and assist in the removal of the ash, and passing steam through the heated firebed, and thereby forming water gas.

6. The method of making water gas in a gas 80 generator having a firebed and an agitating member operating in the lower portion of such firebed, which comprises cooling the walls of the generator in the region of the agitating member, air-blasting the firebed and maintaining a zone therein at an intermediate 85 level at a temperature sufficiently high to liquefy a substantial portion of its ash content, passing said liquefied ash content downwardly from said zone along the parts of the firebed enclosing walls which are immediately 90 above the aforesaid water cooled walls, to the vicinity of said agitating member, without solidifying substantially upon the walls above the water cooled areas thereof, and moving said agitating member through the 95 lower portion of the firebed to engage and break up clinkers before large masses can form, and passing steam through the heated firebed, and thereby forming water gas.

7. The method of making water gas in a gas 100 generator having a firebed and an agitating member operating in the lower portion of the firebed, which comprises proportioning alternate flows of air and steam through the firebed so as to maintain an ash liquefying zone 105 at an intermediate level in the firebed and a second lower zone of somewhat less temperature in the vicinity of the agitating member, passing the liquefied ash content downwardly from said first mentioned zone to said second 110 mentioned zone, moving said agitating member to engage the solidifying ash and break up clinkers, and removing clinker and ash from said lower zone substantially as fast as they are formed therein. 115

8. The method of making water gas in a gas generator having a firebed resting upon a grate and an agitating member moving over said grate, which comprises keeping the hottest zone of the firebed low down near the grate by removing the ashes as fast as they form on said grate, passing steam through the firebed and using more than a 60% ratio of down-run steam to total steam supplied to the firebed, and decreasing the amount of up-run steam accordingly, and agitating the bottom of the firebed to break up the clinkers while hot and before large masses can form. 120

9. The method of making water gas in a 130 gas generator having a firebed, which com-

prises air-blasting and passing steam through the firebed to maintain a zone at an intermediate level therein at a temperature sufficiently high to liquefy a substantial portion of its ash content, passing the liquefied ash content downwardly from said zone, agitating the firebed to prevent blow-holes and break up and remove clinkers while hot and before large masses can form, and preventing 10 said high temperature and absence of blow-holes from resulting in blast gases having over 14% of CO by carrying a relatively thin firebed.

10. The method of making water gas in a gas generator having a relatively thin firebed, which consists in air-blasting the firebed and maintaining a zone therein at an intermediate level at a sufficiently high temperature to liquefy a substantial portion of its 15 ash content, passing the liquefied ash content downwardly to a solidifying zone beneath said first mentioned zone and passing an agitating member through said solidifying zone to break up the clinkers before large masses 20 are formed, and passing steam through the heated firebed, and thereby forming water gas.

11. The method of making water gas in a gas generator having a relatively thin firebed, which consists in air-blasting the firebed and maintaining a zone therein at an intermediate level at a sufficiently high temperature to liquefy a substantial portion of its ash content, passing the liquefied ash content downwardly to a solidifying zone beneath said first mentioned zone, passing an agitating member through said solidifying zone to break up the clinkers before large 25 masses are formed and removing the ashes from the bottom of the firebed as fast as they are formed, and passing steam through the heated firebed, and thereby forming water gas.

12. The method of making water gas in a gas generator having a relatively thin firebed which comprises proportioning alternate

flows of air and steam to maintain a zone at an intermediate level in the firebed at a temperature sufficient to liquefy a substantial portion of its ash content, and agitating the 50 firebed in an upward direction from underneath so that the above conditions of operation will cooperate to avoid the production of blast gases containing more than 14% CO. 55

13. In a method of making water-gas in a gas generator, the steps comprising subjecting the bottom zone of the fuel-bed to a continuous agitating and crushing action, to crush ash-clinker forming near such agitating and crushing zone, continuously discharging the ash and crushed clinkers from said crushing zone, and supplying up-steam in such low amount that, with the given air-supply and down-steam and given fuel, 60 there is maintained just above said crushing zone a hot zone that liquefies ash and causes such liquefied ash to descend substantially to the crushing zone before solidifying into 65 clinker of greater bulk than is crushed by 70 the aforesaid crushing action.

14. In a method of making water gas in a generator having a grate and a fuel bed supported thereon the steps which comprise: maintaining a zone of red heat in the fuel 75 bed immediately above said grate, maintaining a zone of ash melting heat in the fuel bed above said zone of red heat whereby the molten ash runs down into said zone of red heat, and ash melted in said melting zone is 80 prevented from solidifying in masses too large to be crushed, and continuously crushing and removing solidified ash from said zone of red heat at a rate sufficient to prevent its accumulation in said generator, and passing steam through the heated firebed, and thereby forming water gas. 85

Executed at Chicago in the county of Cook and State of Illinois this 30th day of June, 1926.

CHARLES W. ANDREWS.
